UNITED STATES PATENT OFFICE.

GEORGE SINGLETON, OF DOVER, NEW JERSEY.

TENSION DEVICE FOR SILK-SPINNING MACHINES.

SPECIFICATION forming part of Letters Patent No. 340,631, dated April 27, 1886.

Application filed May 19, 1884. Serial No. 132,113. (No model.)

To all whom it may concern:

Be it known that I, GEORGE SINGLETON, a citizen of the United States, residing at Dover, Morris county, State of New Jersey, have invented a new and useful Improvement in Tension Devices for Silk-Spinning Machines, of which the following is a specification, reference being had to the accompanying drawings, forming a part thereof.

10 The object of my invention is to provide a tension device for silk-spinning machines, wherein the strands are kept under a uniform tension during their passage through the machine, and also a device for preserving the tension when the machine is suddenly stopped or when its speed is suddenly increased. These objects I attain by the construction shown, which will be fully explained, and pointed out in the claims.

20 Figure 1 of the drawings is a perspective view of a portion of a silk-spinning machine having my invention attached thereto. Fig. 2 is a detached view of bracket-rolls, guide-wire, and a portion of the rail, the rolls being in section. Fig. 3 is a plan of the same, and Fig. 4 is a transverse sectional elevation of the machine on a line slightly at the right of the thread shown in Fig. 1.

The machine made use of in the application of my invention is provided with a spindle, *b*, driving-cylinder *b*², band *b*', driving-roll *c*, traverse-bar *c*², and guide-rods *c*³, all as is usual in this class of machines, and need not be further described herein.

30 *B* represents an angle-bracket, the foot of which bracket is secured to the rail *d* by means of a screw, *d*', that passes through the foot of the bracket, and which screws in the rail *d*, and which gives ample support to the bracket, to hold the same in the several positions in which the same may be placed for purposes of tension. In the projecting part *B*⁴ of the bracket is suitably arranged and secured a pin, *B*'. On the pin *B*' are arranged 40 tension-rolls *B*² and *B*³, the inner ends of which are dished centrally, while their outer circumference is slightly rounded off, which construction permits the roll *B*³ to jam against the roll *B*², and thereby place tension on the 45 most delicate strand when the stud *B*' is inclined at an angle with the horizon. The yoke-

shaped guide *C* is also secured suitably in the arm *B*⁴ of the bracket *B*, which gives ample support to the guide as well as to the pin *B*', to carry and support the rolls *B*² *B*³. At a 55 suitable distance below the tension-rolls, and journaled in the arm *a*', is a rod, *F*. The rod *F* is provided with a handle, *F*', and has arranged thereon a coil, *f*², having a hook, *f*³, which hook rests on a rod, *f*', which rod is 60 connected to the rod *F* by links *f*⁵, and is operated thereby. In the outer end of the arm *a*' is secured a rod, *f*', over which the spun thread passes to the rolls *B*² *B*³.

The machine is supposed to be in motion, 65 and the operation is as follows: The strand *o*' is taken from the bobbin *o* upward to and partly over the rod *f*', through the hook *f*³, up to the guide *C*, to and between parts *e*' of said guide, to and between the tension-rolls 70 *B*² *B*³, and over the usual guide and traverse bars, *c*² *c*³, up to the receiving-bobbin *c*', which, being in rotation, winds the spun fiber on the same under the influence of the usual traverse mechanism. The tension-roll *B*³, owing 75 to the incline given to the pin *B*', tends continually in the direction of the roll *B*², and into engagement with the strand *o*', and puts the same under tension. The tension may be increased or diminished by simply changing 80 the position of the bracket *B* on the rail *d* by means of the screw *d*', which screw is adapted to hold the bracket in its several positions where the same may be placed for purposes of tension. It will be understood that when the 85 pin *B*' is placed at an increased incline it throws more of the weight of the roll *B*³ on the strand *o*', which will increase the tension of the strand accordingly, and the opposite will be the case when the pin is placed upon a less 90 angle or incline. The rounded form of the guide *C*, as shown at *e*', permits the strand to enter the guide and be guided by the same between the tension-rolls without injury. When the machine is to be brought to a sud- 95 den standstill, the handle *F*' is pulled forward, which action, by means of links *f*⁵, depresses the rod *f*⁴, while the coil *f*², which is in tension, causes the hook *f*³ to follow the rod *f*⁴, and carry with it in the hook's descent the 100 strand *o*', which action keeps the strand taut, and prevents kinks and twisting of the strand

2'. When the machine is started, the handle is pushed back gradually until the rod f^4 is raised in position with the hook, strand, &c. By this my invention a uniform tension is kept on the strand.

Having described my invention, I claim and desire to secure by Letters Patent—

1. The combination, with the roll B^2 and pin B' , for supporting the roll, of the bracket B , the screw d' , for securing the bracket to the rail, the rail d , the guide C , as described, and the tension-roll B^3 , adapted to journal on and
- 10

slide over pin B' , for tension, substantially as and for the purpose set forth.

2. The combination, with the rod F , having handle F' , for operating said rod, of the coil f^2 , arranged on said rod, the links f^5 , the rod f^4 , the hook f^3 , the rod f' , and supporting-arm a' , as and for the purpose set forth.
- 15

GEORGE SINGLETON.
